Primary Examiner — Derrick E Holland*(74) Attorney, Agent, or Firm* — Oblon, McClelland, Maier & Neustadt, L.L.P.(57) **CLAIM**

The ornamental design for a solar canopy, as shown and described.

DESCRIPTION

FIG. 1 is a front, top, and left side perspective view of a solar canopy showing the new design.

FIG. 2 is a rear, bottom, and right side perspective view thereof.

FIG. 3 is a rear elevational view thereof.

FIG. 4 is a front elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken lines depict portions of the solar canopy that form no part of the claimed design.
